UNITED STATES PATENT OFFICE.

CHARLES B. BOTKIN, OF OSAGE, KANSAS.

CAR-COUPLING.

No. 800,063.

Specification of Letters Patent.

Patented Sept. 19, 1905.

Application filed October 6, 1904. Serial No. 227,381.

To all whom it may concern:

Be it known that I, CHARLES B. BOTKIN, a citizen of the United States, residing at Osage, in the county of Osage and State of Kansas, 5 have invented certain new and useful Improvements in Car-Couplers, of which the following is a specification.

My invention pertains to car-couplers, more particularly car-couplers of the "Master Car-Builders" type; and it contemplates the provision of an automatic coupler which is reliable in operation under all conditions and yet is simple and inexpensive in construction and is well adapted to withstand the rough usage 15 to which car-couplers are ordinarily subjected.

The invention will be fully understood from the following description and claim, when taken in connection with the accompanying drawings, forming part of this specification, 20 in which—

Figure 1 is a perspective view of the coupler constituting the present and preferred embodiment of my invention as the same appears when ready to be connected to a complementary coupler without the necessity of a trainman remaining between the cars. Fig. 2 is a vertical section taken through the longitudinal center of the coupler and illustrating the parts in the same relative positions as in Fig. 30 1. Fig. 3 is a view similar to Fig. 2, illustrating the parts in the positions they assume when the coupler is engaged by a complementary coupler. Fig. 4 is a transverse section of the coupler with some parts in elevation and 35 illustrating the latch on the arm of the knuckle. Fig. 5 is a detail vertical section taken in a diagonal plane and illustrating the relative arrangement of the latch-body and the arm of the knuckle when said parts are in the positions shown in Figs. 1 and 2.

Similar letters designate corresponding parts in all of the views of the drawings, referring to which—

A is the draw-head of the coupler. In addition to the usual mouth *a*, the flange *b* at one side of said mouth, and the apertured lugs *c* at the opposite side thereof the said draw-head is provided with a chamber *d*, preferably of angular form in horizontal section, communicating with and extending upwardly from the mouth *a*, and a vertical bore *e*, extending from the top of said chamber to the upper side of the draw-head.

B is a vertical rectilinearly-movable gravitating latch. This latch comprises a body *f*, 55 shaped in cross-section in conformity to and arranged in the chamber *d* of the draw-head, and a stem *g*, suitably connected to the body *f* and extending upwardly therefrom through the bore *e* of the draw-head. The latch may 60 be raised either by a trainman applying his hand to its stem *g* or through the medium of suitable mechanism connected to said stem *g*, as desired, without involving a departure from the scope of my invention. 65

C is a knuckle having the usual reduced portion *h* interposed between the lugs *c* of the draw-head A and connected to said lugs through the medium of a pintle *i*. The said knuckle is also provided with an inwardly-extending arm *j*, which is designed to swing inwardly and outwardly in the mouth *a* of the draw-head. This arm *j* has the upper side of its free portion inclined or pitched rearwardly and downwardly in the direction of the width 75 thereof, as indicated by D and best shown in Fig. 5, for an important purpose hereinafter set forth.

In the practical use of my invention, when the coupler is to be connected to a complementary coupler, the latch B and the knuckle C are relatively arranged, as shown in Figs. 1, 2, and 5—*i. e.*, the latch is arranged with its body *f* resting on the rear portion of the inclined upper side D of the knuckle-arm *j*. 80 From this it follows that when the arm *j* is swung rearwardly by the impingement of the knuckle of a complementary coupler the inclined upper side D of the knuckle-arm *j* will by acting against the lower end of the latch-body *f* first raise the latch, and then after the arm *j* passes the latch-body the latch will 85 drop, so that its said body will rest in the position shown in Fig. 3 to hold the knuckle against casual opening. To permit the knuckle 90 C to swing open and become disconnected from the knuckle of another coupler, it is simply necessary to raise the latch B through the medium of its stem *g*.

The inclined upper side D of the knuckle-arm *j*, which operates to raise the latch B precedent to the passage of said arm from below the latch-body *f*, will be appreciated as an important feature of my invention when it is remembered that in winter ice is liable to 105 gather on the stem *g* of the latch and in the

bore *e* of the draw-head and fasten the latch against downward movement. The positive raising of the latch by the inclined upper side *D* of the knuckle-arm will effectually release 5 the latch from any ice that may gather on or in the coupler, and hence the latch will always fall after the knuckle-arm has passed from below it and assure the proper locking of the knuckle in its closed position.

10 As will be readily apparent, the body *f* lends weight to the latch *B*, so as to assure the quick descent of the latter when released and at the same time places the strain due to the pull on the knuckle *C* on a large portion 15 of the draw-head. The distribution of this strain is also due in part to the fact that in its lower position the latch-body *f* rests in a seat *m* in the bottom wall of the mouth *a*.

It will be gathered from the foregoing that 20 my novel coupler is at once simple and inexpensive in construction, reliable in operation, and calculated to withstand the roughest usage.

While I have described the present embodiment of my invention with the greatest detail in order to impart a definite understanding of said embodiment, I desire it understood that such changes or modifications may be made in practice as fairly fall within the scope 25 of my invention as claimed.

Having thus described the invention, what I claim as new, and desire to secure by Letters Patent, is—

In the car-coupler described, the combination of a draw-head having a mouth, a flange 35 at one side of said mouth and apertured lugs at the opposite side thereof and also having a seat *m* in the bottom wall of the mouth, a chamber communicating with and extending upwardly from the mouth, and a reduced, 40 vertical bore extending from the chamber to its top, a vertical, rectilinearly-movable gravitating latch comprising a body disposed in the chamber of the draw-head and a stem extending upwardly through the vertical bore there- 45 of, and a knuckle pivoted between the lugs of the draw-head and having an arm arranged, when the knuckle is open, to rest under the body of and support the gravitating latch; the upper side *D* of the free portion of said 50 knuckle-arm being inclined downwardly and rearwardly in the direction of its width, for the purpose set forth.

In testimony whereof I affix my signature in presence of two witnesses.

CHARLES B. BOTKIN.
